SCORE CARD

Burnie J. Craig, San Gabriel, Calif.

Application February 2, 1935, Serial No. 4,671

10 Claims.

(Cl. 40—65)

This invention relates to score cards for keeping records or tallies in games or for similar purposes.

One of the specific objects is to provide an improved record card or indicator having means thereon for indicating the record or score made in a number of repeated operations, as e. g. in golf, the number of strokes required to make a hole or in baseball the number of hits, runs, errors, etc., made by the contestants.

Another object of the invention is to provide a record card made of paper or similar material which is assembled, cut and folded in a novel manner.

15 A further object of the invention is to provide a score card having tabs operable to a position beneath an aperture to indicate the score and having novel means to prevent the tabs being moved away from the aperture after the score is registered.

A still further object of the invention is to provide an improved blank from which a score card can be made.

25 An additional object of the invention is to provide novel means for reenforcing a score card cover.

Other objects and the apparent advantages of this invention will be apparent from the following description taken in connection with the 30 accompanying drawings wherein:

Fig. 1 is a top plan view of an assembled blank from which my improved score card is made;

Fig. 2 is a view similar to Fig. 1 showing a blank after the tabs are cut and the apertures 35 punched;

Fig. 3 is a view similar to Fig. 2 showing the tabs folded and inserted.

Fig. 4 is a rear view with the flap portions folded;

40 Fig. 5 is a rear view showing the back in place and partly broken away;

Fig. 6 is a front view of the finished card in use;

Fig. 7 is a fragmentary view taken on line 7—7 of Fig. 3;

45 Fig. 8 is a sectional view through the entire score card taken on line 8—8 of Fig. 5; and,

Fig. 9 is a fragmentary detail with parts broken away.

This invention is an improvement on my prior 50 Patent No. 1,557,924, granted October 20, 1925.

Referring to the drawings by reference characters I have shown my invention as embodied in a score card which is indicated at A. As shown the score card is made from an assembled blank 55 indicated generally at 10. This blank comprises

a cover or front member 11 having flaps 12 thereon and a pair of side filler members 13 and a bottom filler member 14.

The cover is made of suitable paper or other stock. The filler members 13 and 14 are paper sheets and the fillers 13 are secured to the rear side of the front 11 by suitable area of glue indicated by broken lines at 15 while the filler 14 is secured to the rear side of the front 11 by an area of glue indicated by broken lines at 16. 10 The cover and filler may be printed with suitable indicia indicated at 17, prior to assembly or after assembly as desired.

The cover and filler members are each provided with aligning apertures 18 through which 15 the score recorded is viewed. The cover and filler members also have aligning slits 19 which are substantially U-shape to define tongues 20. The filler members are also provided with apertures 21, which are located beyond the edges of 20 the cover flaps 12.

After the card has been punched as shown in Fig. 1 the fillers 13 and 14 are notched as at 22, Fig. 2, to provide tabs 23. If desired the punching and the notching to form the tabs may be 25 performed in one operation.

The tabs 23 are then folded on themselves as shown in Fig. 3 and the ends of the tabs are threaded first through the aperture 21 and then through the slits 19 so that the tabs are directly 30 engaged by the tongues 20 which spring back and close the opening. This presents the free ends of the tabs 23 on the front face of the cover with the ends of the tabs adjacent the apertures 18.

If the cover material is not sufficiently strong a reenforcing panel 24 may be glued or otherwise secured along each edge of the cover and this panel may be cut with the slits 19 and tongues 20. 35

After the parts are in the position shown in Fig. 3 the cover flaps and the filler are folded on fold lines 20'. These fold lines 20' are disposed along the free ends of the tongues 20 and when the flaps 12 are folded the score card parts assume the position shown in Fig. 4 with the 40 ends of the tabs protruding through the slits 19 at the edge of the card so that they can be seized and pulled out until the desired number is in the opening 18.

A protecting member 26 is then preferably 50 placed to overlie the folded tabs 23 and is tucked under the flaps 12 as shown in Fig. 5.

The back 25 which may be of material similar to the front is then glued in place. This back may be glued only along its edges to the flaps 12 55

or it may be glued to both the flaps and to the protecting member 26.

The function of this protecting member is to prevent disalignment of the tabs during assembly 5 of the score card and to prevent any glue getting on the tabs. Since no material is removed when the tongues 28 are punched these tongues completely close the aperture when they are in the position shown in Fig. 5 so that glue does not pass 10 through the slits 19 into the interior of the score card.

It will be noted that the tabs 23 are connected by a wide panel 30 with the cover portion. In construction the distance from the edge 31 of the 15 panel, Fig. 3, to the line viewing apertures 18 is greater than the distance from the edge 31 to the fold line 32 where the tabs are folded on themselves. As a result in the finished card when the tabs are withdrawn any buckles which appear 20 in the portion 33, as shown in Fig. 7, will disappear before this portion reaches the aperture 18 so that there will be no obliteration of indicia on the score card tabs.

In use the score card is assembled as described 25 and the operator pulls a tab, such as shown in Fig. 6, until the correct number appears in the aperture 18. The end of the tab is then torn off flush with the side of the card. This leaves the free end of the tab disposed within the card but 30 this free end passes through the slot 21, as shown in Fig. 9, and therefore the free end cannot move up and down being confined by the walls of this slot so that possible movement of the tab with its indicia is prevented.

From the foregoing description it will be apparent that I have provided a novel score card 35 which is easy to operate, simple in construction and highly efficient in use.

Having thus described my invention, I claim:

1. A score card comprising a body part having 40 a plurality of movable tabs thereon, said body part having viewing apertures therein, each aperture being aligned with a tab, said tabs being disposed with their major portion within the body and with the ends projecting from the body and with the numbers so arranged that as the tab is withdrawn the numbers will be presented beneath the viewing apertures, the end of the tabs being adapted 50 to be torn off whereby the record may be prevented from being accidentally altered and means within the score card to prevent disalignment of the tabs with their respective apertures after the tabs are torn off.

2. A record card comprising a cover part having 55 a plurality of tabs thereon, said tabs being folded so that one part thereof is superimposed on another part, said tabs being tearable and projecting beyond the side of the body part and having indicia thereon, said cover part having 60 apertures therein, and said tabs having characters thereon adapted to be brought into registration with said apertures by movement of each of said tabs, said tabs after being pulled 65 being adapted to be torn off in line with the edge of said cover and slotted guide means within the card and spaced from the edge thereof to prevent disalignment of the tabs with their respective apertures after the tabs are torn off.

3. A record card comprising a polygonal front portion having a plurality of apertures therein and a polygonal back portion united with the front portion along all edges thereof and having slits along one of the edges at the junction of 70 the front and back portions and rupturable re-

cording tabs extending through said slits and having indicia thereon visible through said apertures, said record card having a slotted portion therein spaced inwardly from said slits, each tab extending through a slot in the slotted portion. 5

4. A blank for a record card comprising a cover portion having a plurality of tabs projecting from opposite sides thereof, said blank having sets of three aligned apertures along each side thereof, each set of apertures being disposed in line with 10 a tab, there being a tongue closing the middle aperture of each set.

5. The method of making a record card from a blank including a body portion having tabs thereon which comprises making three apertures in 15 the blank for each tab, folding each tab upon itself, inserting the end of each tab first through one aperture and then through another aperture, then folding the sides of the body portion onto the remainder of the body portion, and securing 20 a back to the body portion.

6. A score card comprising a cover portion having a filler therein, said filler comprising a plurality of tabs, each of said tabs being bent on itself, said filler having apertures therein and the end of said tabs passing through said aperture, said cover having other apertures therein, said tabs passing through said other apertures and projecting beyond the edge of said cover 25 and a back on said cover.

7. A score card comprising a cover portion having a plurality of tabs extending therefrom, said tabs being disposed to overlie the body portion, apertures in said body portion through which 35 said tabs are visible, said tabs projecting at the edge of the score card, a protecting member overlapping said tabs and a back secured to said cover portion.

8. A score card comprising a cover portion having tabs projecting therefrom, a reinforcing 40 strip extending along one edge of said cover portion, a plurality of apertures in said cover portion, certain of said apertures also extending through said reinforcing strip, said cover portion being folded with the line of fold disposed upon 45 said reinforcing strip, said tabs being folded and extending through certain of said apertures and a back secured to said cover portion.

9. A score card comprising a cover portion having a plurality of tabs extending therefrom and having a flap along one side thereof, said flap being folded to overlie the body portion, apertures in said body portion through which 50 said tabs are visible, tongues disposed in said flap, said tongues defining apertures, said tabs extending through said last mentioned apertures and a cover secured to said flap and to said tongues whereby the tongues are held in line with the adjacent material of the flaps.

10. A score card comprising a body part having a panel at one side, said panel being folded to overlap the body part, a plurality of movable tabs projecting from said panel, each tab having numbers thereon, said body part having viewing 65 apertures therein, each aperture being aligned with a tab, said tabs being folded on themselves to provide two tab thicknesses disposed within the body and the numbers being so arranged that as the tab is withdrawn the numbers will be 70 presented beneath the viewing apertures, the end of the tab being adapted to be torn off whereby the record may be prevented from being accidentally altered.
